UNITED STATES PATENT OFFICE.

ANTON HOYER, OF CHICAGO, ILLINOIS.

ADJUSTABLE SUPPORT FOR SMOKE-SHELLS.

996,717.

Specification of Letters Patent.

Patented July 4, 1911.

Application filed May 6, 1910. Serial No. 559,804.

To all whom it may concern:

Be it known that I, ANTON HOYER, a citizen of the United States, and residing at Chicago, in the county of Cook and State 5 of Illinois, have invented a new and useful Improvement in Adjustable Supports for Smoke-Shells, of which the following is a complete specification.

The main objects of this invention are to 10 provide means for supporting smoke shells above gas or other flame lights to protect the ceiling of the room from injury due to smoke and heat from the flame; to provide an adjustable support for smoke shells 15 which may be easily adjusted to bring the shell directly over the flame; to provide means for supporting smoke shells without attaching them to the ceiling; and to provide a very cheap, simple and effective device 20 which is capable of being detachably mounted on the gas pipe or fixture stem.

A specific construction embodying the invention is illustrated in the accompanying drawings, in which:

25 Figure 1 is a side elevation of the adjustable support. Fig. 2 is an enlarged section taken on line 2—2 of Fig. 1. Fig. 3 is an enlarged section taken on line 3—3 of Fig. 1. Fig. 4 is a top plan view of the support. Fig. 5 30 is a fragmentary plan view of the adjustable support adapted to support four shells. Fig. 6 is a fragmentary plan view of the support adapted to support two shells.

In the construction shown the support 35 comprises two bars or other members 1 and 2, which are telescopingly connected together to permit the support to be adjusted longitudinally. Said members may be of any preferred construction and material, but as 40 shown they each comprise a bar or strip of metal having sufficient rigidity to prevent its bending under the weight of the shell, and the adjacent or overlapping ends of the members are forked. The prongs 3 and 4 of the 45 forks are spread apart and bent around the upper and lower edges of the adjacent member, so as to secure the members together but permit each to slide through the fork of the other.

50 The free end 5 of the member 1 is bent around the gas pipe 6 and is brought back against the member and is secured thereto in gripping or clamping engagement about the pipe by means of a loop 7 which is slidably mounted on the member and is adapted

to be forced toward the pipe over said end and to thus hold the end in clamping position.

The free end of the member 2 is provided with a hook 8 which is adapted to support 60 a smoke shell 9 of any desired construction above the gas flame, or light, not shown.

Where two gas lights are mounted on the same pipe 6, two of the adjustable supports may be employed, as shown in Fig. 6, in 65 which case, in order to have them at the same height, the members 1 are formed of a single bar 10 which is curved centrally at 11 to conform to one side of the gas pipe 6, and a short clamping bar 12 is curved centrally at 13, and oppositely from the bar 10 to conform to the opposite side of the pipe. The ends of the bar 12 lie flat against the bar 10 and are secured thereto by means of loops 7.

75 Where it is desired to employ four supports, as shown in Fig. 5, each member 1 is bent near its free end 14 to provide a portion 15 at an angle of 45 degrees to the main portion of the member, and said end is bent 80 at an angle of 90 degrees to the member. Each portion 15 is provided with a slightly curved portion 16 adjacent to the pipe 6. When the members 1 are arranged about the pipe with the end 14 of each member lying 85 against the next adjacent member, the members may be secured in position by the clamping loops 7. The same method may be employed for attaching three supports to the pipe.

90 The operation of the construction shown is as follows: The member 1 is clamped to the pipe by means of the loop 7, which, when forced toward the pipe and over the end of the member, binds the member firmly 95 against the pipe. In this manner the device may be quickly clamped to pipes of various sizes. The member 2 may then be adjusted to bring the hook 8 to the desired distance from the pipe to support the smoke shell 100 directly above the flame.

While but one specific embodiment of the invention has been herein shown and described it will be understood that various details of the construction shown may be 105 varied or omitted without departing from the spirit of the invention.

I claim:

A support for smoke shells, comprising 110 longitudinally adjustable bars adapted to

extend laterally from a gas fixture, each bar having a curved portion near its inner end adapted to bear directly against said fixture, with the end of the bar lying flat against the 5 next adjacent bar, and a loop slidably mounted on each bar and adapted to bind said end thereto.

In witness whereof I have hereunto subscribed my name in the presence of two witnesses.

ANTON HOYER.

Witnesses:

W. W. WITHERBURY,

JOHN CORWIN.
